UNITED STATES PATENT OFFICE.

ELIAS WIRTH-FREY, OF AARAU, SWITZERLAND, ASSIGNOR TO AKTIENGESELLSCHAFT KUMMELER & MATTER, OF AARAU, SWITZERLAND.

EVAPORATOR FOR LIQUIDS.

Application filed January 6, 1920. Serial No. 349,781.

To all whom it may concern:

Be it known that I, ELIAS WIRTH-FREY, a citizen of the Republic of Switzerland, residing at Aarau, Laurenzvorstadt, Switzerland, have invented certain new and useful Improvements in Evaporators for Liquids; and I do hereby declare the following to be a clear, full, and exact description of the invention, such as will enable others skilled in the art to which it appertains to make and use the same, reference being had to the accompanying drawing, and to letters or figures of reference marked thereon, which form a part of this specification.

15 This invention relates to improvements in heat interchange devices and particularly to heating bodies used in evaporating liquids.

Experiments carried out on evaporators for liquids provided with vertical heated 20 channels for the circulation and evaporation of the liquid to be evaporated, have shown that the precipitation in solid form of substances contained in the liquid such as salts, takes place preferably at the upper 25 edge of these channels, thus causing a rapid diminution of the effective area of the passage and of the transmission of heat at these points and it may even lead to a complete filling up of the area of the channels whereupon the evaporation is then made totally 30 impossible.

The object of this invention is to eliminate the drawback referred to. To this end the walls of the channels for the passage of 35 the liquid in the evaporator are provided with a scraping device for the purpose of preventing the formation of scale at the walls of said channels by actuating said scraping device.

40 The accompanying drawing illustrates by way of example two modes of carrying out the invention and a number of details thereof. In this drawing:

Fig. 1 is a vertical section through an 45 evaporator for liquids provided with a heating body of concentrically arranged vertical annular chambers and fitted with a scraping device.

Fig. 2 is a plan thereof.

50 Fig. 3-10 show in front and side views four different exemplifications of the scrapers adapted to work on the upper edge of the heating body.

Fig. 11 is a vertical section through an 55 evaporator provided with a scraping device,

the scraper blades of which extend over the greatest part of the outer surfaces of the heating bodies.

Referring at first to Figs. 1 and 2 of the drawing, 1 designates a cylindrical evaporating vessel. Within this vessel 1 vertical hollow annular heating bodies 2 are arranged concentrically one within the other. The hollow spaces 3 of these bodies communicate with a pipe 4 and by means of a plurality of connecting pipes 5 with each other. The scraper blades 6 are arranged above the upper edges of the heating bodies 2 and act like clamps which project over the upper edges of said bodies. Said scraper blades 6 are fixed to vertical rods 7, which are carried on a horizontal rod 8, the latter being fixed to a vertical shaft 9. A bevel wheel 10 is mounted on said vertical shaft. Any rotating motion imparted to said bevel-wheel 75 causes the scrapers to move along the circular edges of the heating bodies. The vertical rods 7 are adapted to be adjusted along the horizontal rod and the scraper blades 6 are preferably arranged to act in a resilient manner on the heating bodies in order to avoid any troubles that might arise from the edges of the hollow bodies 2 not being uniform in shape when the shaft 9 and with it the scraping device is rotating and making thus a 80 machining of said edges not necessary.

In imparting rotation to the shaft 9 the upper edges of the heating bodies 2 are thus scraped and any precipitation in the act of being deposited removed with the object to 90 maintain a free passage for the circulation of the liquid and to provide for an unrestricted heat interchange between the heating bodies and the liquid.

The scrapers shown in Figs. 3, 4, 7, 8, 9 95 is shown in Figs. 3 and 4 of thick wires, or flat scrapers as shown in Figs. 7 and 8 may be used. Figs. 5 and 6 illustrate scrapers adapted to be used on rectangular edges of heating bodies, and in Figs. 9 and 10 scrapers are shown which are provided with interchangeable shoes 11 acting as scraping faces.

The scrapers shown in Figs. 3, 4, 7, 8, 9 and 10 are bent in such a way that they are 105 pressed by their own spring action in a resilient manner against the surfaces of the heating body, the scraper shown in Figs. 5 and 6 is a plate spring.

Another modification of the scrapers is 110

shown in Fig. 11 which differ from those shown in detail in their respective length in as much as the scrapers shown in Fig. 11 extend over the greater part of the height 5 of the heating bodies.

What I claim now as my invention is:

1. Evaporator for liquids, consisting of a vessel, of vertical hollow annular heating bodies concentrically arranged one 10 within the other and inside the vessel, a scraping rotatable device acting on the outer surfaces of said heating bodies during evaporation and provided with scrapers of clamp shape, for the purpose of preventing the precipitation of scale on said heating bodies.
2. Evaporator for liquids, consisting of a vessel, of vertical annular hollow heating bodies concentrically arranged one within 20 the other and inside the vessel, a scraping device acting on the upper edges of the surfaces of said heating bodies and provided with scrapers of clamp shape, which project over the upper edges of the heating 25 bodies for the purpose of preventing the precipitation of scale on said heating bodies.
3. Evaporator for liquids, consisting of a vessel, of vertical annular hollow heating bodies concentrically arranged one within 30 the other and inside the vessel, a scraping device acting on the upper edges of the surfaces of said heating bodies and provided with scrapers of clamp shape, which project over the upper edges of the heating 35 bodies, said scrapers being carried on a rotatable member acting as beam.
4. Evaporator for liquids, consisting of a vessel, of vertical annular hollow heating bodies concentrically arranged one within 40 the other and inside the vessel, a scraping device acting on the upper edges of the

surfaces of said heating bodies and provided with scrapers which project over the upper edges of the heating bodies, said scrapers being carried on a rotatable beam and arranged adjustably in the direction of the beam for the purpose of preventing the precipitation of scale on said bodies. 45

5. Evaporator for liquids, consisting of a vessel, of vertical annular hollow heating 50 bodies concentrically arranged one within the other and inside the vessel, a scraping device acting on the upper edges of the surfaces of said heating bodies and provided with scrapers which project over the upper 55 edges of the heating bodies, and press against said edges in a resilient manner, said scrapers being carried on a rotatable beam and arranged adjustably in the direction of the beam, for the purpose of preventing the precipitation of substances contained in the liquid to be evaporated in the shape of scale on said bodies. 60

6. Evaporator for liquids, consisting of a vessel, of vertical annular hollow heating 65 bodies, concentrically arranged one within the other and inside the vessel, a scraping device acting on the upper edges of the surfaces of said heating bodies and provided with scrapers which project over the 70 upper edges of the heating bodies and press against said edges in a resilient manner, said scrapers being carried on a rotatable beam and arranged adjustably in the direction of the beam and provided with inter- 75 changeable scraping faces, for the purpose of preventing the precipitation of substances contained in the liquid to be evaporated in the shape of scale on said bodies.

In testimony that I claim the foregoing 80 as my invention, I have signed my name.

ELIAS WIRTH-FREY.
